METHOD AND APPARATUS FOR PUMPING
FLUIDS

George K. Parker, Escalon, Calif.

Application October 22, 1934, Serial No. 749,404
Renewed May 9, 1936

17 Claims. (Cl. 103—75)

This invention relates to a method and apparatus for pumping fluids.

The object of the present invention is to provide a method and apparatus for pumping fluids whereby the fluid body being pumped is counterbalanced. Inertial movement of the fluid body is utilized to induce flow of an additional volume of fluid into said body and surges in the fluid body are employed to assist the movement of a piston or a similar driving element when the pump is operating.

Apparatus whereby the method of pumping may be accomplished is shown by way of illustration in the accompanying drawings, in which:

Fig. 1 is a diagrammatic view showing one form of apparatus whereby the pumping of fluids may be accomplished.

Fig. 2 is a diagrammatic view showing another form of apparatus whereby pumping may be accomplished.

Fig. 3 is a diagrammatic view showing another form of apparatus.

Fig. 4 is a side elevation of the cam drive employed in conjunction with the pumping apparatus shown in Fig. 3.

Fig. 5 is a horizontal section of the cam drive shown in Fig. 1.

Referring to the drawings in detail and particularly Fig. 1, A indicates a pumping conduit and B a balancing conduit. The conduits are connected at their lower ends by a cylinder 2 and at their upper ends by a tank or reservoir 3 which serves to maintain the conduits completely filled with water or other fluid, and which also functions as an overflow or discharge for the fluid being pumped.

Both conduits and the bodies of fluid constrained therein are in communication with the cylinder 2 but are divided or separated with relation to each other by a piston 4 which is driven by an engine generally indicated at C in a manner hereinafter to be described. Conduit A extends as indicated at 5 below the cylinder 2 into a source of supply, such as shown at 6, the source of supply being the water or other fluid to be pumped or elevated to the tank 3. A check valve 7 is mounted in the extension 5 and functions in the usual manner; that is, it automatically opens when suction is applied and conversely closes when subjected to pressure.

The engine indicated at C may be driven by any suitable fluid medium under pressure, such as air, steam, etc. It consists of a cylinder 8 in which is mounted a piston 9, this piston being connected with the pump piston 4 by means of

a rod 10. Two inlet valves 11 and 12 are provided and similarly two exhaust or discharge valves 13 and 14.

In actual operation, let it be assumed that movement of the piston 4 in the direction of arrow a will accelerate the body of fluid in conduit A in an upward direction and the body of fluid in conduit B in a downward direction, and that said accelerating movements are simultaneous. In that case the piston travel will be the accelerating distance and it also must be assumed that this distance is equal to the de-accelerating distance of the bodies in the conduits A and B.

When the piston stops, the acceleration of the bodies A and B will cease but both bodies will continue to travel due to inertia, but de-acceleration will immediately commence the moment movement of the piston ceases. The body A will, during inertial or de-accelerating movement, continue to flow upward. Fluid in the conduit B will impinge against the piston which is at rest and will reverse its initial direction and also flow upward so that while de-accelerating, both bodies A and B are simultaneously flowing upward with diminishing velocity away from the piston for a period of time and through a distance required by the force of gravity to bring the bodies at rest.

While both bodies simultaneously or substantially so are de-accelerating and traveling in an upward direction, a partial vacuum is formed at each side of the piston. During this period, the piston is substantially in static equilibrium and while in this state may be readily returned to its starting point, thus completing one cycle of operation, providing that the accelerating and return travel of the piston are each equal to the de-accelerating distance of the bodies A and B. The accelerating time for the piston being governed artificially by the engine C may be as desired but the return movement of the piston must be in phase with body B de-accelerating, and this is governed by the force of gravity. Hence, it is essential that the piston, while returning, should closely follow body B while de-accelerating in an upward direction.

The inertial displacement of both de-accelerating bodies is concentrated on the side of the piston indicated at 4a, and this space will accordingly be automatically filled from the source of supply indicated at 6 due to the suction action produced. Hence, charging occurs during de-acceleration of the bodies and discharging or pumping equal in volume to the combined inertial

displacement of bodies A and B during the accelerating movement of the piston in the direction of arrow a.

The travel of the piston in the direction of arrow a commences from the position shown in full lines in Fig. 1 where the piston is at rest. The movement is thus slow to commence with but the speed is gradually accelerated until the piston reaches its maximum speed at the end of the stroke. For this reason, the inlet valve 12 is controlled so that the movement of the pistons 9 and 4 will be an accelerating movement with maximum speed at the end of the stroke. The return stroke takes place during the upward de-accelerating movement of the body B and as this movement is rapid, valve 11 will be fully opened so as to return the piston as quickly as possible, the movement, however, being in phase with the de-accelerating movement. The exhaust valve 13 is open when valve 12 is open and conversely exhaust valve 14 is open when the inlet valve 11 is open. The exhaust valves may be fully opened during each stroke of the piston so as to reduce resistance to a minimum but valves 11 and 12 may be gradually and then fully opened to produce the piston movement desired.

The operation of the form of apparatus shown in Fig. 2 is substantially the same. The construction is different. The cylinder containing the driving piston indicated at 4c is mounted at the upper end of the conduit B and so is the driving engine indicated at C. The upper ends of the conduits A and B are connected by a pipe 15 in which is mounted a check valve 16. The lower ends of the conduits are connected by a pipe 17 and both conduits are extended below the pipe 11, as shown at 18 and 19, and the extensions are provided with check valves 20 and 21. It should also be noted that a balanced valve is placed at the point indicated at 22 and that this is actuated by means of a pair of magnets 23 and 24. The stem of the valve extends through the magnets. When the magnet 24 is energized, the valve is moved in the direction of arrow b and is opened, and when the magnet 23 is energized, the valve is moved in the direction opposite to the arrow b and is closed. The operation will be as follows:

When the piston 4c is moved by the engine in the direction of arrow c, check valve 16 will close. Body B will move in a downward direction and as the valve 22 is open, there will be a flow through the pipe 17 and there will also be a flow in an upward direction in the conduit A. At the end of the stroke of the piston 4c, valve 22 is closed by the action of magnet 23. Column A will continue moving due to the motion imparted to it by piston 4c in column B, and a lower pressure area is created in the passage 17 and around the valve 21, causing the same to open and liquid will accordingly be admitted. The downwardly moving liquid in column B rebounds the moment valve 22 closes and there is an upward surging movement in column B. Column B is in communication with pipe 19 and as there will be a reduced pressure area produced therein due to the upwardly surging movement in column B liquid will be admitted.

During the de-accelerating movement of body B, piston 4c is returned and the cycle of operation is completed. The movement of the piston is rapid and in phase with the de-accelerating movement and the check valve 16 will accord-

ingly open admitting fluid to the conduit B. The balanced valve 22 remains closed until the piston starts forward in the direction of arrow c. At that moment it opens and accelerating movement is again imparted to the bodies A and B in the directions previously described, and when the piston reaches the end of its accelerating stroke, valve 22 closes and the cycle of operation is repeated.

Inasmuch as the opening and closing of the valve 22 must be synchronous with the movement of the piston 4c, any suitable means operable from the engine C may be employed for alternately energizing the magnets 23 and 24 so that the valve 22 is opened and closed at the proper time periods.

In the structure shown in Fig. 3, the conduits are again illustrated at A and B. They are connected at their lower ends by a cylinder 25 in which is mounted a piston 26. The upper ends of the conduits are connected by a tank or reservoir 27 and the lower ends of the conduits are both extended, as shown at 28 and 29, into the source of supply shown at 30. Check valves are mounted in these extensions as shown at 31 and 32 and these function as will hereinafter be described. The piston 26 is secured to a rod 33. This extends completely through the cylinder so as to give equal capacity on opposite sides of the piston. The piston rod is in this instance cam driven. A pair of cams are employed as shown at 34 and 35. These are of identical shape and are secured to a common drive shaft 36. The piston rod 33 terminates in a yoke so as to straddle the shaft. Cross-heads 37 and 38 are, however, secured to the rod on opposite sides of the yoke and these are provided with rollers which engage the respective cams, these rollers being arranged in pairs and being indicated at 40-40 and 41-41.

The shaft 36 is driven in any suitable manner, and during such rotation, it should be assumed that the cams engage the rollers 41. If that is the case, movement will be imparted to the rod 33 and the piston 26 in the direction of arrow a. This movement will be an accelerating movement; that is, the piston will move from a point of rest to the opposite end of its stroke and the movement will be an accelerating movement reaching its maximum speed at the opposite end of the stroke. Accelerating movement is thus imparted to the fluid in the conduit A in an upward direction and to the fluid in the conduit B in a downward direction. The fluid in conduit B will impinge against the piston when it comes to rest and the flow will reverse, causing a slight suction action which opens the check valve 32 and thereby admits an additional volume of fluid from the source of supply. The fluid in conduit A continues to move and, as previously described, in an upward direction by inertial movement which is a de-accelerating movement, and during this period, check valve 31 opens and an additional supply is induced through the check valve.

The moment the fluid in conduit A comes to rest, it settles or resurges and strikes the piston with an impact of considerable force, this force being utilized to start movement of the piston when it is returned to its original position shown at 26 in Fig. 3. The cams are at the same time timed so that they will engage the rollers 40-40, and as the cams are shaped to produce an accelerating movement, the movement started by impact action is accelerated and the piston reaches its maximum speed when the end of the

stroke is attained. The accelerating movement is thus imparted to the bodies of fluid in the conduits in the direction opposite to that previously described and the same cycles of operation will take place but in a reverse order to that just described, and when body B resurges, the piston will again receive an impact blow which starts it moving in the direction of arrow a. Hence, both conduits are in this instance used as pumping conduits and the resurging movement of the fluid in the conduits is employed to initiate and assist in imparting movement to the piston.

From the foregoing it should be apparent that a method of pumping fluids has been developed whereby a body of fluid being pumped or elevated will first of all be counterbalanced. Secondly, inertial movement of the fluid in the conduits is utilized to induce the flow of an additional volume of fluid into said conduits and resurges in the fluid bodies are employed to initiate and assist movement of the piston or a similar driving element when the pump is operating.

In view of the fact that the method is capable of employing a variety of forms of apparatus, diagrammatic illustration has been resorted to and while other features have been more or less specifically described and illustrated, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:

1. A method of pumping fluids which consists in maintaining a constrained body of fluid, imparting a gradual accelerating movement to said body of fluid in one direction which reaches a maximum at the end of the movement and utilizing the resultant energy of inertial movement of said body of fluid to induce an additional volume of fluid into the said body of fluid.

2. A method of pumping fluids which consists in maintaining a constrained body of fluid, placing a driving member in said body, applying energy to move the driving member and the body of fluid in one direction a predetermined distance, said movement being an accelerating movement and reaching maximum speed at the end of the movement, and utilizing the resultant energy of inertial movement of the body of fluid to induce an additional volume of fluid into the body.

3. A method of pumping fluids which consists in maintaining a constrained body of fluid, placing a driving member in said body, applying energy to move the driving member and the body of fluid in one direction a predetermined distance, utilizing the resultant energy of inertial movement of the body of fluid to induce an additional volume of fluid into the body, and returning the driving member to its initial position during said inertial movement of the body to induce a second additional volume of fluid into the body.

4. A method of pumping fluids which consists of maintaining two constrained bodies of fluid balanced in relation to each other, imparting movement in the same direction to said bodies said movement being an accelerating movement and reaching maximum speed at the end of the movement, and utilizing the resultant en-

ergy of inertial movement of one of the bodies to induce an additional volume of fluid into that body and the resultant energy of inertial movement of the other body to reverse its initial direction of flow.

5. A method of pumping fluids which consists of maintaining two constrained bodies of fluid balanced in relation to each other, placing a displacement means in said bodies, moving the displacement means and the bodies of fluid in one direction a predetermined distance, utilizing the resultant energy of inertial movement of one of the bodies to induce an additional volume of fluid into that body and the resultant energy of inertial movement of the other body to reverse the direction of initial movement thereof, and returning the displacement means to its initial position during the inertial movement of the bodies to induce a second additional volume of fluid into the bodies.

6. An apparatus for pumping fluids comprising a conduit containing a fluid, said conduit being connected at one end with a source of fluid supply, a check valve in said connection, and means for imparting movement to the fluid in the conduit in one direction, said movement being an accelerating movement and reaching maximum speed at the end of the movement, said means operating intermittently to permit inertial movement of the fluid in the conduit so that the inertial movement of the fluid will produce a suction to open the check valve and induce flow of fluid from the source of supply into the conduit.

7. An apparatus for pumping fluids comprising a conduit containing a fluid, said conduit being connected at one end with a source of fluid supply, a check valve in said connection, a cylinder in communication with the conduit on the effluent side of the check valve, and a piston in said cylinder for imparting movement to the fluid in the conduit in one direction, said movement being an accelerating movement and reaching maximum speed at the end of the movement, said piston operating intermittently to permit inertial movement of the fluid in the conduit while the piston remains at rest so that the inertial movement of the fluid will produce a suction to open the check valve and induce a flow of fluid from the source of supply into the conduit.

8. An apparatus for pumping fluids comprising a conduit containing a fluid, said conduit being connected at one end with a source of fluid supply, a check valve in said connection, a cylinder in communication with the conduit on the effluent side of the check valve, a piston in said cylinder, means for imparting an accelerating movement to the piston and the fluid in the conduit in one direction and abruptly bring the piston to rest at the end of the stroke when the accelerating movement reaches a predetermined maximum speed so as to permit inertial movement of the fluid in the conduit so that a suction will be produced to open the check valve and induce flow of fluid from the source of supply into the conduit.

9. An apparatus for pumping fluids comprising a conduit containing a fluid, said conduit being connected at one end with a source of fluid supply, a check valve in said connection, a cylinder in communication with the conduit on the effluent side of the check valve, a piston in said cylinder, means for imparting an accelerating movement to the piston and the fluid

in the conduit in one direction and abruptly bring the piston to rest at the end of the stroke when the accelerating movement reaches a predetermined maximum speed so as to permit inertial movement of the fluid in the conduit so that a suction will be produced to open the check valve and induce flow of fluid from the source of supply into the conduit, and means for returning the piston to its initial position during 10 said inertial movement of the fluid in the conduit so that an additional suction action is produced to induce further flow from the source of supply into the conduit.

10. An apparatus for pumping fluids comprising a pair of conduits containing a fluid and balanced with relation to each other, one of said conduits being connected with a source of fluid supply, a check valve in said connection, a cylinder connecting the conduits on the effluent 15 side of the check valves, a piston disposed in said cylinder, means for imparting an accelerating movement to the piston and the fluid in the conduits in one direction and abruptly bringing the piston to a rest at the end of its stroke when 20 the accelerating movement of the piston reaches a predetermined maximum speed so as to permit inertial movement of the fluid in the conduits, said inertial movement of the fluid in one producing a suction to open the check 25 valve and to produce flow of fluid from the source of supply into said conduit.

11. An apparatus for pumping fluids comprising a pair of conduits containing a fluid and balanced with relation to each other, one of said 30 conduits being connected with a source of fluid supply, a check valve in said connection, a cylinder connecting the conduits on the effluent side of the check valves, a piston disposed in said cylinder, means for imparting an accelerating 35 movement to the piston and the fluid in the conduits in one direction and abruptly bringing the piston to a rest at the end of its stroke when the accelerating movement of the piston reaches a predetermined maximum speed so as to permit inertial movement of the fluid in one 40 conduit, to induce a flow of fluid through the check valve into said conduit and the resultant inertial movement of the fluid in the other conduit to impact the piston and reverse the flow of the fluid.

12. An apparatus for pumping fluids comprising a pair of conduits containing a fluid and balanced with relation to each other, one of said conduits being connected with a source of fluid supply, a check valve in said connection, a cylinder connecting the conduits on the effluent side of the check valves, a piston disposed in said cylinder, means for imparting an accelerating movement to the piston and the fluid in the conduits in one direction and abruptly bringing the piston to a rest at the end of its stroke when the accelerating movement of the piston reaches a predetermined maximum speed so as to permit inertial movement of the fluid in one of the conduits to induce a flow of fluid through the check valve into said conduit and the resultant inertial movement of the fluid in the other conduit to impact the piston and reverse the flow of the fluid, and means returning the piston to its initial position during the period of reverse flow in the last-named conduit.

13. An apparatus for pumping fluids comprising a pair of conduits containing a fluid and balanced with relation to each other, a connection between each conduit and a source of

fluid supply, a check valve in each connection, a cylinder connecting the conduits on the effluent side of the check valves, a piston in said cylinder, and means for imparting a gradual accelerating stroke to the piston in each direction followed by a period of rest at the end of each stroke, the speed of the piston reaching maximum at the end of each stroke.

14. An apparatus for pumping fluids comprising a pair of conduits containing a fluid and balanced with relation to each other, a connection between each conduit and a source of fluid supply, a check valve in each connection, a cylinder connecting the conduits on the effluent side of the check valves, a piston in said cylinder, and means for imparting a gradual accelerating stroke to the piston in each direction followed by a period of rest at the end of each stroke, the speed of the piston reaching maximum at the end of each stroke, whereby a resurging movement of the fluid in the conduits alternately takes place and imparts an impact blow against the piston to start the piston moving at the commencement of each stroke.

15. An apparatus for pumping fluids comprising a pair of conduits containing a fluid and balanced with relation to each other, a connection between each conduit and a source of fluid supply, a check valve in each connection, a cylinder connecting the conduits on the effluent side of the check valves, a piston in said cylinder, means for imparting first a fluid impact and then a gradual accelerating movement to the piston in one direction and bringing the piston to an abrupt stop and to rest at the end of the stroke when maximum speed is reached and then a second fluid impact followed by a gradual accelerating movement in the opposite direction and bringing the piston to an abrupt stop and to rest at the end of the stroke when the maximum speed is reached.

16. In a pumping system employing a pair of conduits filled with a fluid in which the conduits are connected by a cylinder to balance the fluid in the conduits and in which the fluid is maintained in continuous oscillation in the conduits by a piston reciprocably mounted in the cylinder, a method of driving the piston and for inducing the flow of an additional volume intermittently into each conduit, which consists in starting the movement of the piston in each direction by an impact blow alternately imparted to the piston by resurging movement in each conduit, imparting a gradual accelerating movement to the piston in each direction after it has been started by an impact blow, bringing the piston to an abrupt stop at the end of the stroke when the accelerating movement reaches a maximum speed, and intermittently utilizing inertial movement of the fluid in the respective conduits to induce the flow of an additional volume of fluid into said conduits from a source of supply.

17. In a pumping system employing two constrained bodies of fluid, each body being connected with a source of supply and also connected with each other by a communicating cylinder adapted to balance the bodies and in which the bodies are maintained in continuous oscillation by a piston reciprocably mounted in the cylinder, a method of driving the piston and for inducing the flow of an additional volume of fluid intermittently into each body which consists in starting the movement of the piston in each direction by an impact blow alternately imparted to the piston by a resurging movement

of each body, imparting a gradual accelerating movement to the piston in each direction after it has been started by an impact blow, bringing the piston to an abrupt stop at the end of the stroke when the accelerating movement reaches a maximum speed, and intermittently utilizing

the energy of the inertial movement of each body of fluid respectively to induce the flow of an additional volume of fluid into the said bodies from a source of supply.
